PEDESTAL PUNCH

Filed June 4, 1921

Patented June 12, 1923.

1,458,328

UNITED STATES PATENT OFFICE.

JESSE DITSON AND ARTHUR E. PETERS, OF LITTLETON, COLORADO, ASSIGNEES TO INGERSOLL-RAND COMPANY, OF JERSEY CITY, NEW JERSEY, A CORPORATION OF NEW JERSEY.

PEDESTAL PUNCH.

Application filed June 4, 1921. Serial No. 474,883.

To all whom it may concern:

Be it known that we, JESSE DITSON and ARTHUR E. PETERS, citizens of the United States, and residents of Littleton, county of 5 Arapahoe, State of Colorado, have invented a certain Pedestal Punch, of which the following is a specification, accompanied by drawings.

This invention relates to machines for 10 punching hollow drill steels and similar articles, but more particularly to a pedestal punch in which the punching mechanism is mounted at one side of a pedestal or other support and the clamping mechanism for 15 clamping the hollow article is mounted at the other side of the pedestal, although my improved clamping mechanism is capable of use in other arrangements, and not necessarily with the particular form of punching 20 mechanism shown herein, the details of which punching mechanism are disclosed in our co-pending joint application, Serial No. 435,476, filed January 6, 1921.

The objects of the present invention are 25 to secure a simple and efficient pedestal punch combining punching mechanism and clamping mechanism capable of being readily assembled and disassembled, and mounted on a pedestal with few parts which 30 do not readily get out of order under frequent and hard usage. Another object is to produce a clamping mechanism capable of aligning and centering various sizes of 35 drill steels within its range and is at the same time quick in operation, both in gripping and releasing the steel and holds equally rigidly in both directions.

Our application is shown in one of its preferred forms in the accompanying drawings in which—

Figure 1 is a side elevation partly in longitudinal section of a machine embodying the invention;

Figure 2 is a transverse vertical sectional view on the line 2—2 of Figure 1 looking in the direction of the arrows;

Figure 3 is a detail sectional view of the vise jaw levers in open position;

Figure 4 is a detail perspective view of the 50 female vise jaw lever, and

Figure 5 is a similar view of the male vise jaw lever.

Referring to the drawings, the pedestal A is provided with the head B having a bore

through which a guide bar C is adapted to 55 be passed horizontally and held in position by means of the tightening bolts D. The guide bar C forms a ready and convenient common support and guide for both the fluid actuated punching mechanism E preferably 60 slidable upon one projecting portion of the guide bar and the fluid actuated clamping mechanism F adapted to be suitably secured to the opposite projecting portion 65 of the guide bar. A hollow drill steel G is shown clamped in the clamping mechanism in position to be punched by the pin H, as the punching mechanism is moved towards the steel.

Only so much of the punching mechanism 70 is shown as will serve to illustrate the invention, since the details of the punching mechanism covered by the aforesaid application Serial No. 435,476 forms no part of the present invention. The punching 75 mechanism comprises a unitary casing J having a portion K forming a slide through which the guide bar C passes, and a fluid pressure cylinder L preferably of the hammer type may be provided with a hammer 80 piston (not shown) adapted to impart blows of impact to the punch H for driving it into the article to be punched.

The punching mechanism may be moved 85 back and forth on the guide bar C in any suitable manner as for instance by means of the hand operating lever O pivoted at P on the pedestal A and connected to the lug Q on the casing of the punching mechanism by means of the link or rod R, pivoted to the lever O at the point S. The connecting rod 90 R may be provided with the collar T and a cushioning spring U is arranged between said collar and a washer V bearing against the lug Q. Another cushioning spring W 95 is arranged between the washer X and an adjusting nut Y on the screw threaded end k of the connecting rod. By manipulating the hand lever O the punching mechanism E may be pulled toward the article to be punched and pushed away from the article 100 when the punching operation is completed.

The guide bar C is preferably provided with a longitudinal groove a and the casing is provided with a key or feather b secured thereto by means of the screws c so that as the punching mechanism is moved forwardly and backwardly, the key b maintains the 105

mechanism in alignment with the article to be punched.

The hammer cylinder L is provided with the back head d and fluid pressure is admitted to the punching mechanism through the inlet e and controlled by the valve f shown in this instance as a valve of the poppet type, having a valve stem g. The back head d is provided with the supply 10 passage h leading to the cylinder.

The outer end of the guide bar C is provided with a cam surface j in the form of a groove in the guide and a hardened tappet o is adapted to move vertically in a socket p in the rearward extension q of the casing J. A locking pin r extends into the groove s in the tappet to limit its movement. The stem g of the poppet valve f extends through a removable screw threaded plug t forming a 20 valve cage so that the valve as well as the valve cage may be removed for grinding. The valve stem g is adapted to bear on the tappet o and with the parts in the position indicated in Figure 1, the tappet o lies on 25 the cam surface j and the controlling valve f is closed. In such position the casing of the punching mechanism lies against the stop u secured to the rearward end of the guide bar C as by means of the cap screw v.

30 In starting the punching mechanism in operation, the initial movement of the casing J forwardly along the guide bar C towards the article to be punched, causes the tappet o to move out of the groove forming the cam 35 surface j and pushes the poppet valve o open thus admitting live fluid pressure to the hammer cylinder L. The valve f is maintained open during the forward and backward movement of the punching mechanism 40 and automatically closes when the punching mechanism is returned to its initial position against the stop u as indicated in Figure 1.

The clamping mechanism F for clamping the drill steel G or other article to be 45 punched comprises a vise head 2 provided with a sleeve or body portion 3 adapted to be passed over the opposite projecting end of the guide bar C and held upon the guide bar by means of the stop 4 and cap screw 5.

50 Set screws 6 assist in holding the vise head in proper position and alignment on the guide bar.

The vise head 2 is provided with a fluid 55 pressure cylinder 7 having a reciprocating piston 8 the piston rod 9 of which is guided in a piston rod guide 10 in the form of a yoke adapted to be secured across the lower open end of the cylinder 7 as by means of the bolts 11. A spring 12 is adapted to be 60 compressed between the piston and the piston rod guide 10 when the piston is forced outwardly and downwardly in the cylinder so that the spring returns the piston in the cylinder. Motive fluid is supplied to the 65 cylinder through the connection 13 and

supply port 14 controlled by the throttle valve 15 in the usual manner. Fluid exhausts from the cylinder through the exhaust port 16.

Vise jaw clamping levers preferably in the form of male and female levers indicated in detail in Figures 4 and 5 are suitably pivoted horizontally on the vise head as by means of the pin 17 about which the levers are adapted to rock in clamping and releasing the drill steel G or other article to be punched. The female lever 18 is forked or double in form and provided with the jaw head 19, and the tongue 20 of the male lever 21 is adapted to be inserted between the double or forked portion of the female lever so that the clamping head 22 lies opposite the clamping head 19. Hardened vise jaws 23 and 24 are adapted to be removably secured to the jaw heads of the levers as by means of the bolts 25.

The outer ends of the vise jaw levers 18 and 21 are pivotally connected as shown, to the piston 8 of the cylinder 7 by suitable operative means shown in this instance as 90 lift levers 26 pivoted at 27 to the vise jaw levers and pivoted at 28 to the skirt of the piston. As the piston 8 moves downwardly the jaws are closed and they are released and opened when the piston moves upwardly 95 and inwardly.

The extensions 29 on the vise head 2 to which the vise jaw levers are pivoted as shown, extend upwardly at each side of the lever jaws and are hollow or concave in form 100 as indicated in Figures 2 and 3 to form rests for the drill steel or other article to be punched upon which the article is placed when the jaws are open as indicated in Figure 3. When the jaws move toward each 105 other to closed position the drill steel is picked up by the vise jaws and centered automatically as indicated in Figures 1 and 2 in alignment with the punch H.

In the operation of the machine, a drill 110 steel or other article to be punched is placed in the clamping mechanism upon the rests 29 as indicated in Figure 3 with the clamping jaws open. Fluid is admitted to the cylinder 7 and the piston 8 is forced downwardly thereby rocking the vise jaw levers on their pivot 17 and automatically clamping and centering the article to be punched in the position indicated in Figure 2. The manual operating lever O is then grasped 120 by the operator and the punching mechanism is pulled toward the article to be punched so that the pin H enters the article and is withdrawn therefrom as the punching mechanism is pushed backwardly.

We claim:

1. A machine for punching hollow drill steels and similar articles, comprising a support, a guide bar carried by said support, punching mechanism slidable upon said 130

guide bar, a vise head adapted to be sleeved over said guide bar, jaw levers pivoted on said vise head, a cylinder and fluid actuated piston for said vise head, lift levers operatively connecting said piston and the jaw levers, and means for controlling the operation of said piston.

2. Clamping mechanism for a punching machine comprising a vise head, a vertical cylinder and fluid actuated piston therein, horizontally extending jaw levers pivoted to said vise head above the cylinder, lift levers operatively connected to said jaw levers and piston and means for controlling the supply 10 of motive fluid to said cylinder, whereby downward travel of the piston rocks the jaw levers to clamp an article to be punched.

3. A machine for punching hollow drill steels and similar articles, comprising a support, clamping mechanism mounted on said support and consisting of a vise head, jaw levers pivoted on said vise head, a cylinder and fluid actuated piston for said vise head, lift levers operatively connecting said piston 20

and jaw levers, means for controlling the 25 operation of the piston, and punching mechanism mounted on the support and movable to and from the clamping mechanism.

4. A machine for punching hollow drill steels and similar articles, comprising a support, clamping mechanism mounted on said support and consisting of a vise head, a vertical cylinder and fluid actuated piston therein, horizontally extending jaw levers pivoted to said vise head above the cylinder, 30 lift levers operatively connected to said jaw levers and piston, means for controlling the supply of motive fluid to said cylinder, whereby downward travel of the piston rocks the jaw levers to clamp an article to be 35 punched, and punching mechanism mounted on the support and movable to and from the clamping mechanism.

In testimony whereof we have signed this specification.

JESSE DITSON.

ARTHUR E. PETERS.
